Patented Feb. 22, 1921.

FIG. 1

FIG. 2

Inventor
John S. Helling
by Robert W. Jenner
Attorney

UNITED STATES PATENT OFFICE.

JOHN S. HELLING, OF VISALIA, CALIFORNIA.

INSECT-TRAP.

1,369,429.

Specification of Letters Patent. Patented Feb. 22, 1921.

Application filed August 21, 1920. Serial No. 405,113.

To all whom it may concern:

Be it known that I, JOHN S. HELLING, a citizen of the United States, residing at Visalia, in the county of Tulare and State 5 of California, have invented certain new and useful Improvements in Insect-Traps, of which the following is a specification.

This invention relates to mechanical traps for killing insects, and more particularly to 10 power driven devices for swatting flies; and it consists in the novel construction and combination of the parts hereinafter fully described and claimed.

In the drawings, Figure 1 is a side view of 15 a device for killing flies and other similar insects, constructed according to this invention. Fig. 2 is a plan view of the same.

A casing 4 is provided for inclosing a suitable spring motor or clockwork time 20 mechanism for operating the swatter. The motor driving shaft 5 projects from the casing, and has a disk 6 secured on it and provided with a crank-pin 7. The disk 6 is revolved in the direction of the arrow adjacent to it, by the spring 8 inside the casing. A lever 9 is pivoted to the casing by a pin 10, and it has a longitudinal slot 12 in one end portion, which slot engages with the crank-pin 7. The other end portion of the 25 lever is provided with a fly swatter 14 formed of a plate or sheet of any suitable light material, such as the woven wire used in making fly-screens for windows.

A catch 15 is pivoted to the casing below 30 the lever 9, by a pin 16, and the catch is preferably provided with a longitudinal slot 17 so that it may slide lengthwise on the pin 16 to a limited extent. The lever 9 is normally supported in an inclined position, as 35 shown in Fig. 1, by means of a detent 18, which projects radially from the disk 6, and which bears against the lower end of the catch 15.

A spring 19 is secured between the lower 40 end portion of the catch and the casing 4, so that the middle part of the slot 17 engages with the pin 16 when the detent is pressing against the end of the catch. The upper end portion of the catch is a little 45 heavier than its lower end portion, so that the lower end portion normally rests against the underside of the lever 9 adjacent to the crank-pin, being provided with a lateral projection 23.

50 A cam 20 is secured on a shaft 21 which projects from the casing 4. This shaft 21

is revolved constantly by the time mechanism or clockwork 24 inside the casing, in the direction of the arrow adjacent to the cam, and the time mechanism is arranged so that the cam will trip the catch 15 periodically, and preferably two or three times a minute.

A flat plate 25 is arranged in the path of the swatter. Sugar or other approved bait, 55 is placed on the plate 25, and the flies or other insects attracted by it are crushed against the plate by the swatter at each descent of the same. The swatter lever is operated suddenly, the disk being arranged 60 to be moved for a whole revolution by the driving spring 8 before the detent engages again with the end of the catch. The slot 17 slides a little over the pivot pin when the detent strikes the catch so that its upper 65 end is projected into the path of the cam to a predetermined extent, and the catch is thereby caused to work smoothly and with certainty. The spring 8 does not revolve 70 the disk 6 and the crank-pin and operate 75 the lever 9 when the parts are in the positions shown, because the upward pressure of the crank-pin 7 on the part of the lever above the slot is not sufficient to disengage 80 the detent 18 from the end of the lever 15. 85 The weight of the upper end portion of the lever 15 presses its lower end and the part 23 upwardly into the angle between the detent 18 and the lever 9, and the spring-actuated crank-pin presses the detent hard against 90 the end of the lever 15.

What I claim is:

1. The combination, with a supporting plate for the bait, of a pivoted lever provided at one end with a swatter for striking the said plate, a spring-operated crank-pin engaging with the other end portion of the said lever, a detent projecting from the said lever, a pivoted catch which normally engages with the said lever and with its detent, 95 and a time-controlled cam which retracts the catch at predetermined intervals.

2. The combination, with a plate for the bait, of a pivoted lever provided at one end portion with a swatter for striking the plate 100 and having a longitudinal slot in its other end portion, a disk provided with a crank-pin which engages with the said slot, a spring for revolving the said disk, a catch normally preventing the lever from being 105 operated, and a time-controlled cam which operates the catch at predetermined inter-

vals and permits the swatter to strike the plate and return to its raised position.

3. The combination, with a plate for the bait, of a pivoted lever provided with a swatter for striking the said plate, driving devices for oscillating the said lever, a pivoted catch provided with a slot which permits it to slide longitudinally, a detent projecting from the said disk and bearing 10 against one end of the catch, a spring hold-

ing the catch in contact with the detent, and a time-controlled cam which engages with the other end of the catch at periodic intervals and releases the detent, thereby permitting the swatter to strike the plate and return to its original position. 15

In testimony whereof I have affixed my signature.

JOHN S. HELLING.
